WOVEN WIRE PARTITION

Walter A. Bishoff, Sr., Louisville, and Leonard B. Ulery, Jeffersontown, Ky., assignors to Logan Co., Louisville, Ky., a corporation of Kentucky

Filed May 23, 1967, Ser. No. 640,695

7 Claims. (Cl. 256—24)

ABSTRACT OF THE DISCLOSURE

Block members are placed in the adjacent vertical channels forming part of the frames of woven wire partitions to prevent the edges of the channels when brought into engagement with each other from slipping laterally and "telescoping" relative to each other, to facilitate the assembling of the channels, the blocks being so constructed as to receive and provide for the crimping of certain of the wires of each panel, thus eliminating the necessity for welding or otherwise fixing the blocks in the channels.

Background of the invention

The panels embodying the present invention are old per se and comprise channel frame members within which are arranged heavy woven wire bodies. The vertical channel members are outwardly opened, and in assembling two partition units with respect to each other the edges of the flanges of the vertical channels are brought into contacting relation, whereupon the two channels are bolted together. The panels are used for making partitions in stockrooms, or any other desired place, and the assembling of the channels, requiring the bringing of the edges of the vertical channels into engagement is sometimes interfered with and delayed due to the slipping of a flange of each channel into the other channel. This requires the pulling back of one channel and the realigning of the channels, and requires particular care in exactly aligning the channels before the bolts can be applied.

Summary of the invention

The invention comprises blocks, usually of cast iron, arranged in each vertical channel and shaped in a novel way to receive ends of certain meeting wires of the woven wire bodies of the panels, the extremities of the wires being crimped over to anchor the wires relative to the channels and to anchor the blocks in position without having to weld or otherwise secure the blocks. The side of each block from which the wires enter is provided with a conical opening to facilitate the insertion of the wires, and the outer faces of the blocks are grooved to provide space to receive the crimped ends of the wires. The blocks substantially fill the widths of the channels so that in assembling them relative to each other the channels cannot "telescope."

Brief description of the drawing

FIGURE 1 is a face view showing one panel and the edge portion of a next adjacent panel;

FIGURE 2 is an enlarged fragmentary vertical sectional view showing two adjacent connected vertical channels, parts being broken away;

FIGURE 3 is a detailed sectional view on line 3—3 of FIGURE 2;

FIGURE 4 is a slightly enlarged perspective view of one side of one of the blocks; and

FIGURE 5 is a similar view showing the other side of a block.

Description of the preferred embodiment

Referring to the drawing, the numeral 10 designates each of a plurality of woven wire partition units. Each of

2

these units is provided with a channel section frame comprising a lower channel 12, an upper channel 14 (FIGURE 2) and vertical side channels 16. As shown in FIGURE 3, the vertical channels of adjacent panel units open toward each other and have the edges of their flanges in direct contact with each other.

Each panel further comprises a woven wire body 18 connected to the four frame members in the manner shown in FIGURE 2. For example, wires extend through openings 20 in the bases of the channels and are crimped over as at 22 to anchor the wires in position. All of the wires are so anchored in conventional partition units of this type. When the vertical channels of adjacent units are brought together as shown in FIGURE 3, they are tightly connected together by bolts 24 extending through openings 26 in the bases of the channel members.

The present invention comprises a plurality of blocks 28 per se and in combination with the partition units. These blocks are preferably economically formed of cast iron and are identical in form. They are generally square in face profile and each has one face 30 facing away from the base of the channel. The width of each block is slightly less than the width of each channel to make certain that the blocks seat against the channel bases without any interference from the filleted corners within the channels or any inaccuracies in manufacture. The faces of each block are vertical and the face 30 is grooved as at 34 for a purpose to be described.

Each block is provided centrally thereof with an opening 36 therethrough and this opening tapers to increase in size as at 38 through the opposite face 40 of the block. It will be noted that the horizontal depth of each block is not greater than the internal depth of each channel so that the faces of adjacent blocks may substantially contact while allowing the edges of the channel flanges to come solidly into contact.

In assembling each panel it is preferred that two blocks be employed in each vertical channel, as suggested in FIGURE 2. The wires of the woven wire body are inserted through the openings 20 and those wires which are to be connected to the blocks 28 are inserted through openings 42. With the latter wires extending straight through the channel, that is horizontally, one of the blocks is pressed into position over each such pair of wires, the tapered opening 36 guiding the wires through the opening 36, thus facilitating the placing of each block in position. The wires are then crimped over as at 44 (FIGURE 2), the crimped ends lying in the grooves 34 of the blocks. The crimping is done in the usual manner and serves to anchor each block 28 to its associated channel with no necessity for having to weld or otherwise secure the blocks in position.

As previously stated, it is quite easy for the flange edges of the vertical channels to slip laterally so that these channels "telescope" relative to each other. This is particularly true when rolls of the mills which manufacture the channels have become worn and one flange will be thicker than the other. With the present invention, if the channel edges are slightly misaligned, they can be directly moved laterally into alignment without having to horizontally back-off a partition channel which is to be connected to one already in position. Thus, much time is saved in the assembling of a plurality of partition units. An operator may grasp the tops of two channels and readily align them with one hand while he utilizes the other hand for inserting a bolt 24 into position. The bottoms of the vertical channels may be similarly aligned and bolted. After the partition is completed, an inverted channel cap 46 (FIGURES 1 and 2) may be placed over and extend throughout the length of the fin-

ished partition. This cap member forms no part of the present invention.

It is to be understood that the form of the invention shown and described is to be taken as a preferred example of the same and that various changes in the size, shape and arrangement of parts may be made as do not depart from the spirit of the invention or the scope of the appended claims.

What is claimed is:

1. A partition made up of connected sections each of which comprises vertical and horizontal frame members and a body filling the space within said frame members, each of said vertical frame members having flanges defining a channel, the channels of the vertical members opening away from each other whereby adjacent vertical channels of adjacent sections may be assembled with their flanges in edge-to-edge relation, means for connecting said adjacent vertical channels to each other when in such edge-to-edge relation, and at least one block arranged in at least one of said adjacent vertical channels to prevent a flange of one adjacent channel from "telescoping" into the other channel prior to the securing of such channels to each other.

2. A partition according to claim 1 wherein at least two substantially vertically spaced blocks are arranged in each of said adjacent channels.

3. A partition according to claim 1 wherein said body is formed of woven wire, at least two substantially vertically spaced blocks being arranged in each of said adjacent vertical channels, the bases of said vertical channels being provided with openings through which wires of said body project and which wires are crimped over within the channels to anchor said wire bodies to the channels, each of said blocks being arranged in alignment with one of said openings and having an opening therethrough through which certain of said wires can project, the ends of such latter wires being crimped over against said blocks at the sides thereof remote from the bases of said associated channels to retain said blocks in

position, the crimping of said latter wires forming the sole means for maintaining said blocks in said channels.

4. A partition according to claim 3 wherein said opening in each of said blocks tapers to increase in size toward the associated channel base to assist in guiding said latter wires through the openings in said blocks.

5. A partition according to claim 3 wherein the sides of said blocks remote from their associated channel bases are vertically grooved to receive the crimped ends of said latter wires.

10 6. A partition according to claim 3 wherein the sides of said blocks remote from their associated channel bases are vertically grooved to receive the crimped ends of said latter wires, the opening in each block being tapered to increase in size toward the associated channel base to facilitate the insertion of said latter wires through such opening prior to the crimping thereof.

15 7. A partition according to claim 6 wherein each block has vertical sides adjacent the flanges of the associated vertical channel, each block being of a depth not greater than the internal depth of the vertical channel in which it is arranged.
